3 Claims.

(Cl. 38—66)

This invention relates to laundry ironing machines, either of the single or multiple heated bed type and has more particular reference to the ironing beds therefor.

The ironing beds of these machines when of cast iron construction are liable to crack even if carefully heated up by the operator; beds which have been installed some time may on occasion crack for no apparent reason when the steam for heating is turned on in the usual way. It has been found that if beds instead of being cast hollow in the well known way are made of solid form with steam heating pipes running therethrough there is no liability of cracking during operation but owing to the length and cross-sectional shape of the beds they are subjected to distortion under heat. These problems have been solved according to the invention and beds are provided which are not liable to crack and which are subject to little or no distortion when heated for operation.

The invention consists in providing a solid bed plate heated by contiguous or embedded or partially embedded steam pipes and in equalising or substantially equalising the stresses due to expansion (or contraction) on heating (or cooling) on either side of a horizontal plane containing a neutral axis. The neutral axis is thought to be that passing through or near the centre of gravity of the bed.

The balancing of the stresses to preserve the longitudinal rectitude of the bed may be obtained by controlling the admission of steam to the pipes, as for example by initially admitting steam to certain only of the pipes and later, after the bed has been heated to a temperature approaching the ultimate temperature required, or other predetermined temperature, admitting steam to the remaining pipes to raise the temperature to that finally required. By raising the temperature of the bed in stages it has been found that there is no substantial distortion and that the shape of the bed is preserved adequately for all practical purposes.

The balancing or equalisation may be effected either by predetermining the steam pipe heating area on opposite sides of the horizontal plane containing the neutral axis to compensate for the distorting stresses, as by embedding the steam pipes to different depths, varying the number and/or diameter of the pipes, or by distributing the heating means equally over the bed area and adjusting the centre of gravity plane by adding metal to that part of the bed which lies below said plane to render the heating area on one side

of the plane substantially equal to that on the other side.

In the accompanying drawings which illustrate two forms of a bed section for a multiple roll ironer,

Figure 1 is an inverted plan of one form of bed plate,

Figure 2 is a side elevation,

Figure 3 is a cross section on the line 3—3 of Figure 1,

Figure 4 is a diagrammatic view showing the coupling of the steam pipes,

Figure 5 is a cross section of a modified arrangement of the bed plate and steam pipes.

In carrying the invention into effect according to one convenient mode as described by way of example and wherein the equalisation of stresses is effected by the controlled admission of steam into the steam pipes, an ironing bed section 20

of the usual contour for a multiple bed ironing machine, that is to say, having a concave trough portion 21 with convex portions 22 at either side

each constituting one-half of the crest between the trough portions of the beds of the machine, is cast in the form of a solid curved plate with a set of steam tubes numbered 1 to 16 which are partially embedded in the lower side of the plate.

The set of tubes may be equally spaced and symmetrical about a central vertical plane but for constructional conditions the spacing of the pipes

1 to 8 differs from that of pipes 9 to 16 as will be seen in Figure 3. In a bed of this character the plane containing the neutral axis indicated by the line x, x, Figure 3, intersects the bed adjacent

the zone where the trough part 21 merges into the convex portions 22.

According to the distribution of the steam pipes shown, three (14, 15 and 16) and two and one half (1, 2 and part of 3) pipes lie above the neutral plane x, x in the right and left crest portions respectively while below the neutral plane

ten and one half (part of 3 and 4 to 13) pipes are located below the neutral plane. This proportion may vary according to the pitch of pipes, or other circumstances as may be required.

The pipes are connected in parallel to steam supply and exhaust headers and according to a suitable arrangement for heating the beds in two stages certain of the pipes are connected to separate headers or otherwise provided with means

so that steam may be separately admitted to such pipes. With an arrangement of 16 pipes in each bed disposed as indicated above, counting from one end, Nos. 1, 3, 7, 10, 13 and 15 are connected by pipes 23 (see Figure 4) to one supply header

24 or under the control of one valve and constitute one set of pipes, whilst the Nos. 2, 4, 5, 6, 8, 9, 11, 12, 14 and 16 form the second set and are connected by pipes 25 to another header 26 or 5 under the control of another valve. The pipes 23 and 25 are connected to the respective pipes 1 to 16 by nipples 29.

10 The first set of pipes is coupled to an exhaust header 27, while the second set is coupled to an exhaust header 28.

15 It is preferred to arrange the inlet headers 24 and 26 at opposite ends of the bed section.

16 It will be appreciated that the inlet and exhaust headers 24, 26, 27 and 28 extend the full 15 length of the ironer bed and are connected to a series of bed sections similar to that illustrated. Alternatively, each bed section in a multiple ironer may be provided with its own headers so that the temperature conditions of the several 20 sections may be independently controlled.

20 In operating according to the above described form of the invention, steam is admitted to the first set of pipes through the header 24 for a period and until the bed has reached a temperature of about 275° F. or other predetermined 25 temperature. When this temperature has been reached steam is admitted to the second set of remaining pipes through the header 26 so that the temperature of the bed is brought up to 310° 30 F. or to any required temperature.

30 It will be noted that the bed plate 20 gradually thickens in cross section from the crest or convex portions 22 to the central concave trough portion 21 which has the effect of lowering the 35 position of the neutral plane x—x.

35 In casting a bed plate 20 the pipes 1 to 16 are held in their proper position by spaced plates 30, the ends 31 of which are cast into lugs 32 on the bed plate.

40 With another arrangement Nos. 1, 2, 3, 5, 7, 9, 11, 13, 14, 15 and 16 are connected to one header, whilst Nos. 4, 8, 10 and 12 are connected to another header. Any other arrangement of pipes 45 may be adopted to secure an equal or approximately equal distribution of the stresses during the first heating stage.

45 In carrying the invention into effect according to another mode (see Figure 5) the steam pipes 33 are embedded at suitably spaced intervals in a bed plate 34 of the general form already described. Below the trough portion of the bed, however, additional metal in the form, for example of an I-shaped girder part 35, is cast in with the bed, or the bed is cast with a flattened 50 portion adapted to be machined and to receive

the machined face of an I-girder or other rib of suitable form to add substance to the bed. Alternatively, the separately attached mass of metal may be made practically integral with the bed by bolting it to the bed with an intermediate conducting layer of copper or other metal. According to this arrangement the horizontal plane containing the neutral axis of the bed is lowered to such a degree that the number of pipes or heating area above said plane is the same or substantially the same as that below, so that the stresses tending to distort the bed longitudinally are substantially balanced. The girder part 35 may be heated by the provision of steam pipes embedded or partially embedded 15 in such part. In a somewhat similar manner the stresses may be balanced in a bed of curved plate form of uniform cross-section by differentially embedding the steam pipes above and below the neutral plane, or by making the heating area 20 of the pipes above the plane balance those below the plane by increasing the number of pipes on one side and by placing them closer together or by making the pipes of different cross-sectional shape, or by substituting pipes of smaller 25 diameter at closer pitch. In some circumstances it may be desirable to effect a balancing of the stresses by combining one or more of the modes above described, for example the desired effect may be secured partly by steam control and 30 partly by a constructional arrangement.

We claim:

1. In an ironing apparatus the combination of a plate having a central concave portion and convex end portions, a plurality of steam pipes 35 carried by the plate, said steam pipes being divided into two groups, the pipes of one group being separated by the pipes of the other group, and two steam headers, one connected to each of the two groups of pipes, whereby one group 40 of pipes may be heated independently of the other group to effect a stage heating of the plate.

2. In an ironing apparatus, the combination as claimed in claim 1, wherein the pipes lie in both the concave portion and the convex end 45 portions.

3. In an ironing apparatus, the combination as claimed in claim 1, wherein the pipes of each group lie in both the concave portion and the convex end portions.
